COMBINED TABLE LAMP AND SIGNAL FOR RESTAURANTS AND THE LIKE

Eugene Hervey, 4847 Don Drive, Dallas, Tex.

Filed May 10, 1963, Ser. No. 74,835

Term of patent 14 years

(Cl. D48—20)

FIGURE 1 is a perspective view of a combined table lamp and signal for restaurants and the like embodying my new design.

The broken line showing of a control panel and wire in FIG. 1 is for illustrative purposes only.

I claim:

The ornamental design for a combined table lamp and signal for restaurants and the like, substantially as shown and described.
